COMBINED AUTOMOBILE ARMREST AND COOLER BOX

Frank M. Weaver, Safford, Ariz., assignor to T.I.C., Inc.

Filed Apr. 11, 1973, Ser. No. 349,977

Term of patent 14 years

Int. Cl. D3—01; D12—16
U.S. Cl. D87—1 R

FIG. 1 is a front, top and left side perspective view of a combined automobile armrest and cooler box showing my new design; and

FIG. 2 is a rear, bottom and right side perspective view.

I claim:

The ornamental design for a combined automobile armrest and cooler box, as shown and described.
